UNITED STATES PATENT OFFICE.

ERNST LINDNER, OF BROOKLYN, NEW YORK.

DESIGN FOR AN INCANDESCENT-GAS-BURNER FIXTURE.

SPECIFICATION forming part of Design No. 28,099, dated December 28, 1897.

Application filed November 15, 1897. Serial No. 658,644. Term of patent 7 years.

To all whom it may concern:

Be it known that I, ERNST LINDNER, a citizen of the United States, residing at Brooklyn, Kings county, and State of New York, have invented and produced a new and original Design for an Incandescent-Gas-Burner Fixture, of which the following is a specification, reference being had to the accompanying drawing, forming a part thereof.

10 The annexed drawing illustrates a view in elevation of an incandescent-gas-burner fixture embodying my design.

The object of my invention is to produce a new and original design for an incandescent-gas-burner fixture; and the invention resides 15 in the configuration or shape of the burner-fixture, substantially as shown in the drawing.

The design for the burner-fixture comprises 20 the cylindrical box-like portion A, having a bead *a* at the bottom and surmounted by a series of steps *b*. Below the cylindrical box-

like portion A is the cylindrical portion B of less diameter than portion A and having at its bottom the bead *c*. Surmounting the step-like top of the portion A is the basket-like portion C, having slots of irregular outline and a rim *d*, and projecting from rim *d* is a series of upwardly-turned fingers *e*.

The distinctive feature of the design is the cylindrical box-like portion A, with a series of 25 steps at its top surmounted by the basket-like portion C.

I claim—

The design for an incandescent-gas-burner fixture substantially as shown. 30

Signed at New York, N. Y., the 11th day of November, 1897.

ERNST LINDNER.
